ESTERS OF FLACOURTIACEA ALCOHOLS

Ozren Stefanović and Georg Stefanović, Zemun,
Yugoslavia

No Drawing. Application February 20, 1937, Serial No. 126,938. In Yugoslavia February 27, 1936

3 Claims. (Cl. 260—457)

This invention relates to lipid-soluble substances having bactericidal properties.

It is known that the following substances have a killing action towards acid-resisting bacteria: 5 oils from varieties of Flacourtiacea (Hydnocarpus, Asterostigma macrocarpa, Carpotroche brasiliensis Endl., Oncoba echinata Oliver, Taraktogenos Kurzii King), as well as the acids and alcohols obtained from these oils; further high 10 molecular alicyclic-aliphatic acids, such as high molecular cyclopropyl-, cyclopentyl-, cyclohexyl-fatty acids, and in fact all these acids as such or as their esters, salts, or addition products. The said substances have been investigated in 15 vitro, in vivo, and on the bed of sickness in the case of infections by acid-resisting bacteria, but have been found to be insufficiently active and have for the most part been given up, partly also on account of undesired subsidiary actions. 20 According to the present invention the Flacourtiacea alcohols which essentially consist of the compounds of the formula:

30 wherein n stands for the numbers 10 and 12 are employed in the form of their acid esters or ester salts with polybasic inorganic acids. It has unexpectedly been found that these acid esters as well as the ester salts both in vitro and particularly in vivo show especial bactericidal 35 properties, and in fact not only against acid-resisting bacteria but also against other varieties of pathogenic bacteria. In therapeutic doses they have no auxiliary effect in vivo and consequently they have a high therapeutic index.

40 The preparation of these bactericidal acid esters of the Flacourtiacea alcohols with polybasic inorganic acids proceeds according to generally known methods. The Flacourtiacea alcohols themselves are obtainable in the following manner:

45 The oils of the Flacourtiacea (Asterostigma macrocarpa, Carpotroche brasiliensis Endl., Hydnocarpus, Oncoba echinata Oliver, Taraktogenos Kurzii King) are reduced individually or in admixture, but in such a way that double bonds present remain unchanged, or are only partly reduced. It is obvious that this reduction can be carried out not only with the oils themselves, but that the same may first be saponified and

the acids obtained in this way which substantially consist of chaulmoogric acid of the formula

and hydnocarpus acid of the formula

converted into other esters, e. g. ethyl esters, whereupon they are then reduced individually or in admixture to the corresponding alcohols.

The Flacourtiacea alcohols obtained in this 15 way are converted in the known manner into the acid esters or ester salts of polybasic inorganic acids, such as phosphoric and sulfuric acid.

The substances prepared in this way may be 20 used in the form of the ester salts as healing agents for bacterial infections, particularly with acid-resisting bacteria.

Example.—100 grams of Flacourtiacea oil are 25 heated in 500 grams absolute ethanol until the oil is completely dissolved. 50 grams of sodium are then added in small pieces to this solution in the course of about ten minutes. About a quarter of an hour after the addition of the sodium, the mixture is heated up to the boiling 30 of the ethanol and further heated until all the sodium has completely disappeared, which takes about one hour. After addition of 200 cc. of water the ethanol is distilled off as far as possible in vacuum, and the remaining mixture, when it has cooled down, is mixed with about 750 cc. 35 of water, acidified and extracted with 500 cc. ether. The ether is separated off and washed first with water, then with 3% potassium carbonate, and finally with water again up to the point of neutral reaction.

The ethereal solution is dried by means of sodium sulphate, the ether distilled off and the mixture of alcohols obtained is distilled in high vacuum. Boiling point (at 0.1 mm. pressure) 130–170°. Yield 97%.

The alcohols obtained in this way are converted into phosphoric acid esters according to the following method:

10 parts of the alcohol obtained by reduction 50 are dissolved in 40 parts of absolute ether and 6 parts of phosphorus pentoxide are added thereto. The whole mixture is heated for 24 hours up to the boiling of the ether. The whole is then cooled down to 0° and decantation is effected from 55

- the phosphoric acids which have separated out. The ethereal solution is vaporised in vacuum, the esters of phosphoric acids are taken up with water, and for purification purposes precipitated 5 yet again with common salt or alcohol. The yield corresponds to that calculated. The phosphoric acid esters obtained thus melt at 103-104°, are readily soluble in water with swelling, readily soluble in ether, benzene, olive oil, and insoluble 10 in alcohol. The esters obtained thus are used in aqueous solution in the form of neutral reacting salts.
- The sulphuric acid ester is obtained according to the following process:
- 15 100 grams of the said alcohols are dissolved in 1 litre of absolute ether, this solution is then added drop-wise to a solution of 50 grams of chlorsulphonic acid in 1 litre of ether with stirring and cooling, and the whole allowed to stand for twelve hours. About 100 cc. of water are then added, the ether is evaporated off in vacuum, 500 20 grams of water are then added again and this solution is saturated with common salt, whereupon the sulphuric acid esters precipitate out. In order to purify the same the esters are repeatedly dissolved in water and salted out. The sulphuric acid esters obtained in this way are 25

readily soluble in water with swelling, and readily soluble in ether and olive oil. They are used in aqueous solution in the form of neutral reacting salts.

What we claim is:

1. The acid esters of Flacourtiacea alcohols obtained by carboxylic reduction of the acids present in Flacourtiacea oils but with maintenance of their double bond, with phosphoric acid, which esters are lipoid-soluble substances having bactericidal properties and form neutral water-soluble salts. 10

2. The acid esters of Flacourtiacea alcohols with a polybasic inorganic acid of the group consisting of phosphoric and sulfuric acid, which esters are lipoid-soluble substances having bactericidal properties and form neutral water-soluble salts. 15

3. The acid esters of Flacourtiacea alcohols, obtained by carboxylic reduction of the acids present in Flacourtiacea oils but with maintenance of their double bond, with sulfuric acid, which esters are lipoid-soluble substances having bactericidal properties and form neutral water- 20 soluble salts. 25
